Primary Examiner — Barbara Fox*Assistant Examiner* — Alyse Joseph(74) *Attorney, Agent, or Firm* — Maginot, Moore & Beck LLP(57) **CLAIM**

The ornamental design for a display screen with graphical user interface, as shown and described.

DESCRIPTION

FIG. 1 is a front view of a first embodiment of a display screen with graphical user interface showing my new design; and,

FIG. 2 is a front view of a second embodiment of a display screen with graphical user interface showing my new design.

The broken lines shown in the drawings illustrate portions of the display screen with graphical user interface that form no part of the claimed design.

1 Claim, 2 Drawing Sheets(56)
